UNITED STATES PATENT OFFICE.

JEROME JOSEPH SMIDDY, OF HONOLULU, TERRITORY OF HAWAII.

TOOTH-BRUSH.

1,033,743.

Specification of Letters Patent. Patented July 23, 1912.

Application filed August 13, 1910. Serial No. 576,948.

To all whom it may concern:

Be it known that I, JEROME J. SMIDDY, a citizen of the United States, residing at Honolulu, in the county of Honolulu and

5 Territory of Hawaii, have invented new and useful Improvements in Tooth-Brushes, of which the following is a specification.

This invention relates to tooth brushes and the object of the invention is the provision of a brush adapted for this purpose having means to feed a quantity of a suitable cleansing compound to the bristles.

A further object of the invention is the provision of a brush of this character 15 wherein the feeding of the cleansing compound may be instantly stopped so as to prevent excessive amounts of the cleansing compound being fed to the bristles.

A further object of the invention is the 20 provision of a novel tooth brush having a cylinder-like handle and a plunger working therein which forces a quantity of cleaning compound to the bristles through a channel formed in the brush handle and when released forms a vacuum in the cylinder which 25 acts instantaneously to cut off the feed of the cleaning compound.

Further objects of the invention will appear as the following specific description 30 is read in connection with the accompanying drawing which forms a part of this application, and in which:

Figure 1 is a perspective view. Fig. 2 is a longitudinal sectional view. Fig. 3 is a 35 similar section showing the plunger operated against the tension of the spring for expelling the dentifrice.

Referring more particularly to the drawings, 1 represents the head of the brush which has mounted therein the usual bristles 2 and 3 the connecting neck which joins the head with the handle 4. In this instance the handle 4 is hollowed out to form a piston cylinder 5 in which is mounted 45 a piston 6 having a piston rod 7 connected thereto and extending through a bushed closing cap 8 which is screwed into the end of the cylinder and forms a guide for the piston rod 7. The piston rod 7 is 50 normally forced toward the head of the

brush by a light spiral spring 9 so that the operating button 10 is normally held in engagement with the outer side of the closing cap 8.

The cylinder 5 is supplied with a suitable 55 quantity of any preferred cleansing compound which is fed to the bristles through a longitudinal channel 11 whose entrance into the chamber 5 is arranged at the rear end of the handle. The channel extends 60 parallel with the cylinder 5 through the handle and from thence through the neck to the head 1 where it communicates with transverse grooves or channels 12 leading 65 to the bristles 2.

In the operation of the device, the piston rod 7 is withdrawn through the guiding cap 8 bringing the piston head 6 toward the same and thereby compressing the cleansing compound within the cylinder 5 70 and expelling a portion of it through the channels 11 and 12 to the bristles. Immediately upon release of the piston rod 7 the piston 6 is projected toward the head 75 of the brush and a substantial vacuum is formed in the chamber which instantaneously cuts off the flow or feed of the compound.

Having thus described the invention, what is claimed is—

A tooth brush comprising a handle having a longitudinal passage therein and a channel communicating with the rear end of said passage and extending forwardly to the brush head thereof, said brush head 85 being provided with bristles and with openings located adjacent said bristles and communicating with said channel, a piston movable in the passage of said handle and adapted to eject material from said passage 90 into the channel of said handle, a cap removably holding said piston in place and a spring in said passage adapted to hold the piston inwardly.

In testimony whereof I affix my signature 95 in presence of two witnesses.

JEROME JOSEPH SMIDDY.
